UNITED STATES PATENT OFFICE

2,465,615

HARNESS STOP MOTION ATTACHMENT
FOR LOOMS

John R. Svancarek, Homewood, Ill.

Application May 28, 1946, Serial No. 672,730

7 Claims. (Cl. 139—337)

1

This invention relates to improvements in looms, and more particularly to a harness stop motion attachment therefor.

An object of the invention is to provide an improved harness stop motion attachment for looms which will automatically stop the loom in case of a heddle-strap break.

Another object of the invention is to provide an improved harness stop motion attachment for looms which will not only stop the loom from operation should a heddle-strap break, but will also close a switch mechanism for operating an audible or visual signal so that the loom operator will immediately know when a heddle-strap breaks thereby permitting the heddle frame to fall on the contact bar of the attachment to stop the loom and to close the circuit to an audible or visual signal which will indicate to the loom operator that there is trouble.

Another object of the invention is to provide improved means for completing the electrical circuit in the event of disarrangement or dropping of one or both ends of the harness frame, as happens when the straps for actuating the same become stretched or broken, so that the loom will automatically stop.

A further object of the invention is to provide improved attachments for looms, one of which will be mounted in each end of a group of harness frames to be engaged by a heddle frame should the heddle-strap break, to stop the motion of the loom and to close the circuit to an audible signal to notify the loom operator that there has been a breakage.

Other objects will appear as the description proceeds.

In the accompanying drawings which form a part of this application,

Figure 1 is a side elevation of a loom frame showing a heddle frame supported therein and a pair of the improved harness stop motion attachments in position below said heddle frame;

Figure 2 is a side elevation of one of the improved stop motion attachment devices showing the resiliently supported contact bar and the spaced switch mechanism for connection with the audible signal, and

Figure 3 is a sectional view taken on the line 3—3 of Figure 2.

Like characters of reference are used throughout the following specification and the accompanying drawings to designate corresponding parts.

In carrying out the invention, there is provided an improved loom frame having two spaced uprights 1 and 2 having a cross bar 3 and a head bar 4.

The heddle frame 5 is shown supported by the two straps or cords 6 and 7 passing over the pulleys 8 and 9 supported upon the head bar 4.

2

Disposed under each end of the heddle frame 5 is a stand having a base member 10 and vertically extending frame members 11 and 12, which are slotted adjacent their upper ends and adjustably support the upper frame members 13 and 14. The frame members 13 and 14 are connected together by means of the spaced transversely extending bars or rails 15 and 16, and support the bolts 17 and 18 extending through said frame members 13 and 14 and through the slots 19 and 20 formed in the lower frame members 11 and 12, whereby the upper frame members may be adjusted to a position immediately below the said heddle frame 5.

Inwardly directed angle irons 21 and 22 are secured to the inside surfaces of the upper frame members 13 and 14 by means of the bolts 23 and 24, and said angle members adjustably support the contact heads 25 and 26 formed on the upper ends of the screws 27 and 28 which are threaded through the horizontally extending portions of the angle members 21 and 22, and are held in the desired adjusted position by means of the nuts 29 and 30 disposed above and below each of said angle members 21 and 22.

The contact bar 31 is provided with a metal strip 32 extending along its undersurface for co-operation with the contact heads 25 and 26. A bracket 33 will be secured to the lower surface of the metal plate 32 and will be provided with a transverse pivot shaft 34 upon which the eye of the contact bar supporting rod 35 is mounted. The rod 35 extends through an aperture in the upper cross frame member 15 and a spring 36 is positioned about said rod 35 to resiliently support said contact bar. A second bracket 37 is secured to the undersurface of a metal plate on the contact bar 31 and is provided with the bearing pin 38 which supports the eye at the upper end of the guide rod 39, which likewise extends through an aperture in the cross frame member 15 so that the contact bar will be held in proper alignment underneath the series of heddle frames. An electric wire 40 will be secured between the metal angle brackets 21 and 22 to electrically connect the same, and an electric wire 41 and the wire 42 attached to the metal strip 32 on the contact bar 31 will be connected with a battery 43 and a bell 44 or red signal lamp, whereby

should one of the heddle-straps or ropes 6 and 7 for each heddle frame break or in the event that a warp end is broken or unduly slack, the heddle frame will be dropped on the contact bar 31, thereby forcing the same downwardly to engage the base contact heads 25 and 26, thereby closing the circuit to the battery 43 and 44 which will cause the electric bell 44 or red signal lamp to operate thus warning the loom operator that there has been a breakage. If desired, these attachments located at either end of the heddle

frames and below the same may be arranged to stop the operation of the loom when a heddle frame is released below its proper level.

From the foregoing description, it will be apparent that there has been provided a highly efficient construction of harness stop motion attachment for looms, which will be positive in action and relatively inexpensive to manufacture and produce.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. In combination with a loom having a harness frame, an electric stop motion comprising a stand disposed below the frame, extension members adjustably supported by the stand, contact members secured to said extension members, transverse rails connected to said extension members, means for supporting a contact bar on said rails, an electric circuit having one end connected to the contact bar and the opposite end secured to the contact members, means installed in said circuit for emitting a signal when the circuit is closed by the engagement of the contact bar with the contact members.

2. In combination with a loom having a harness frame, an electric stop motion comprising a stand disposed below the frame, extension members adjustably supported by the stand, contact members secured to said extension members, transverse rails connected to said extension members, means for supporting a contact bar on said rails, an electric circuit having one end connected to the contact bar and the opposite end secured to the contact members, means installed in said circuit for emitting a signal when the circuit is closed by the engagement of the contact bar with the contact members, said contact bar supporting means including a pair of depending shafts inserted in apertures formed in the transverse rails, and connected to said contact bar, means for selectively retaining the bar out of engagement with the contact member.

3. In combination with a loom having a harness frame, an electric stop motion comprising a stand disposed below the frame, extension members adjustably supported by the stand, contact members secured to said extension members, transverse rails connected to said extension members, means for supporting a contact bar on said rails, an electric circuit having one end connected to the contact bar and the opposite end secured to the contact members, means installed in said circuit for emitting a signal when the circuit is closed by the engagement of the contact bar with the contact members, said contact bar supporting means including a pair of depending shafts inserted in apertures formed in the transverse rails, and connected to said contact bar, means for selectively retaining the bar out of engagement with the contact member, said last-mentioned means including a spring received around one of the shafts above the transverse rails.

4. In combination with a loom having a harness frame, an electric stop motion comprising a

stand disposed below the frame, extension members adjustably supported by the stand, contact members secured to said extension members, transverse rails connected to said extension members, means for supporting a contact bar on said rails, an electric circuit having one end connected to the contact bar and the opposite end secured to the contact members, means installed in said circuit for emitting a signal when the circuit is closed by the engagement of the contact bar with the contact members, said contact members comprising inwardly directed angle irons secured to the inside surface of the extension member adjacent the upper end thereof, adjustable screws supported by the angle irons.

5. In combination with a loom having a harness frame, an electric stop motion comprising a stand disposed below the frame, extension members adjustably supported by the stand, contact members secured to said extension members, transverse rails connected to said extension members, means for supporting a contact bar on said rails, an electric circuit having one end connected to the contact bar and the opposite end secured to the contact members, means installed in said circuit for emitting a signal when the circuit is closed by the engagement of the contact bar with the contact members, said signalling means including a bell.

6. In combination with a loom having a harness frame, an electric stop motion comprising a stand disposed below the frame, extension members adjustably supported by the stand, contact members secured to said extension members, transverse rails connected to said extension members, means for supporting a contact bar on said rails, an electric circuit having one end connected to the contact bar and the opposite end secured to the contact members, means installed in said circuit for emitting a signal when the circuit is closed by the engagement of the contact bar with the contact members, said signalling means including a light.

7. In combination with a loom having a harness frame, an electric stop motion comprising a stand disposed below the frame, at each end of the frame, extension members adjustably supported by said stands, contact members secured to said extension members adjacent the upper end thereof, transverse rails connected to said extension members, a pair of shafts vertically supported in said rails, a contact bar supported by said shafts, resilient means to retain said bar spaced above the extension members, an electric circuit having one end connected to the contact bar and the opposite end secured to the contact members, means installed in said circuit for emitting a signal when the circuit is closed by the engagement of the contact members by the contact bar.
